DESIGN FOR A RELIEF VALVE FOR PRESSURE COOKERS OR THE LIKE

Nicholas W. Keller, New Kensington, Pa., assignor to The Aluminum Cooking Utensil Company, New Kensington, Pa., a corporation of Pennsylvania

Application January 8, 1945, Serial No. 117,329

Term of patent 14 years

(Cl. D78—1)

To all whom it may concern:

Be it known that I, Nicholas W. Keller, a citizen of the United States, residing at New Kensington, in the county of Westmoreland and State of Pennsylvania, have invented a new, original, and ornamental Design for a Relief Valve for Pressure Cookers or the like, of which the following is a specification, reference being had to the accompanying drawing, forming a part thereof, in which:

Figure 1 is a top plan view of a relief valve

for pressure cookers or the like showing my new design;

Figure 2 is an elevational view of one side thereof; and

Figure 3 is a perspective view of the top, one end, and the other side thereof.

I claim:

The ornamental design for a relief valve for pressure cookers or the like, as shown.

NICHOLAS W. KELLER.
